ATTORNEY

UNITED STATES PATENT OFFICE.

JOB W. FOST, OF PEABODY, KANSAS.

INK-BOTTLE STOPPER.

1,241,947.

Specification of Letters Patent.

Patented Oct. 2, 1917.

Application filed January 2, 1917. Serial No. 140,271.

To all whom it may concern:

Be it known that I, JOB W. FOST, a citizen of the United States, residing at Peabody, in the county of Marion and State of Kansas, have invented new and useful Improvements in Ink-Bottle Stoppers, of which the following is a specification.

This invention relates to improvements in ink bottle stoppers.

10 An object of the invention is an improvement in ink bottle stopper and particularly to a stopper provided with automatic means for closing the same.

Another object of the invention is the provision of a stopper of the class described that will tightly seal the bottle to prevent accidental spilling of the contents, but which can be readily operated upon the insertion of the pen to feed a predetermined 20 quantity of ink.

Another object of the invention is the provision of adjusting means whereby the amount of ink which is to be fed to the pen can be controlled to suit the writer.

25 Further objects of the invention will be apparent from the following description taken in connection with the accompanying drawings, in which:

Figure 1 is a vertical sectional view 30 through the bottle showing the closing means in normal or closed position.

Fig. 2 is a similar view showing the closing means in its operated or open position.

Referring to the drawings A represents 35 an ink bottle of the ordinary construction and B the closure thereof. The closure B is provided with an opening which is reduced and threaded at its lower end to receive the exteriorly threaded lower extremity of the cylinder 10 which is flared outwardly at the top, and provided at the lower end with an inwardly extending annular flange 11, which provides a valve seat 12. Positioned within the cylinder is a 40 cup 13 provided with an outwardly extending flared upper portion 14 which bears against the inner face of the cylinder and serves to guide the same in its movement. The cup 13 is provided with a plurality of

openings 17 at its lower end to establish 50 communication between the bottle and the interior of the cup when the same is moved to operated position. Secured to the lower extremity of the cup 13 is a semi-spherical shaped valve 15 which is of larger diameter 55 than the opening formed by the inwardly extending flange 11, and is adapted to seat against the valve seat 12. A spring 16 is interposed between the cylinder 10 and the cup 13 tending to hold the valve in its closed 60 and outermost position by exerting its pressure against the outwardly extending flare 14 and the inwardly extending flange 11.

In operation of the device upon the insertion of the pen the grip portion of the 65 same contacts with the outwardly extending flare 14, and upon downward pressure of the same the cup is moved to a lowered position unseating the valve 15 and submerging 70 the lower portion of the cup in the fluid whereby through the medium of openings 17, the pen is fed.

It will be noted from the construction 75 that the quantity of fluid to be fed to the pen may be regulated through the medium of the threads provided at the lower extremity of the cylinder.

From the foregoing description it will be seen that I have provided a bottle stopper of novel construction which will not only 80 prevent accidental spilling of the contents, but will also serve as a gage to prevent over feeding of the pen.

I claim:

1. In combination with the neck of a bottle, of a closure therefor having an opening, a cylinder adjustably mounted within the closure provided at one end with an inwardly extending annular flange, an outwardly flared cup arranged for sliding 90 movement within the cylinder having openings formed in the lower end thereof, a valve secured upon the lower end of the cup, and a coil spring encircling the cup and confined between the inwardly extending annular flange of the cylinder and the flared end of the cup for moving the cup to valve seating position against the flange. 95

2. In combination with the neck of a bottle, of a closure provided with a centrally arranged vertical opening, a cylinder adjustable within the closure, and provided
5 with an annular flange at the bottom, an outwardly flared cup arranged for sliding movement within the cylinder, openings in

the lower end of the cup, a valve secured upon the lower end of the cup, and means for moving the cup outwardly to cause the 10 valve to seat against the annular flange.

In testimony whereof I affix my signature.

JOB W. FOST.
